MOUNTING FOR PANELS

Lytle Gale Hunter, Flushing, N. Y., assignor to
Hunter Sash Company, Inc., Flushing, N. Y., a
corporation of New York

Application October 31, 1938, Serial No. 237,983

2 Claims. (CL 189—78)

This invention relates to a novel and improved form of mounting for panels, the novel features of which will be best understood from the following description and the annexed drawing, in which I have shown a selected embodiment of the invention and in which:

Fig. 1 is a face view of a frame having a panel mounted therein according to this invention;

Fig. 2 is a section on an enlarged scale taken substantially on the line 2—2 of Fig. 1 but without the panel or mounting therefor;

Figs. 3 and 4 are views similar to Fig. 2 but showing successive steps in securing the panel in position;

Fig. 5 is a view on an enlarged scale on the same plane as Fig. 4 and showing part of the structure therein more plainly, and also showing a slight modification;

Fig. 6 is a cross section of the strip in its normal condition before it is inserted in place in the mounting.

The invention is shown as used to mount a panel of glass in a metal frame formed of one piece, this being a situation in which the invention finds particular utility. Such a frame is indicated by the numeral 1 and surrounds an opening closed by a glass panel 2. The frame surrounds a central opening 3 which is closed by the panel, and it will be seen that the panel is larger than the opening. This opening is formed in the rear wall 4 of the frame, and this frame is shown as of U-shape having a front wall 5 with an opening 6 therein which is enough larger than the panel 2 so that the panel may be inserted therethrough into some such position as shown in Fig. 3 wherein it overlaps the wall 4. A suitable backing 7 of felt or any other suitable material may be used between the edge portion of the panel and the adjacent portion of the wall 4.

Between the walls 4 and 5 and outwardly of the edge of the panel is a recess 8. For the purpose of convenience I shall use the word "outwardly" with reference to the center of the panel and shall refer to the top of the panel shown in Figs. 3, 4, and 5 as the face thereof, and the opposite surface as the back thereof. These terms of course are used in a relative sense and not in a limiting sense.

Between the wall 5 and the front face of the panel 2 is disposed a strip 9 of resilient flexible material. The material best suited for the purpose is soft rubber in its resilient flexible state and therefore, for the purpose of convenience, I shall hereinafter refer to the strip as rubber,

although if other materials are found suitable for the purpose they may be used without departing from the scope of the invention. It will be understood that preferably the arrangement shown at two opposite edges of the panel, in Fig. 4, is followed completely around the panel, on all edges thereof.

The strip 9 is of the same general form as the strip shown in my prior Patent 1,891,932. It is used in a different manner, however, with relation to the frame and in such a way as to greatly simplify the construction of the frame over what is shown in said prior patent.

After the panel is placed on the backing 7 as shown in Fig. 3, the strip 9 may be inserted in place by forcing the toe 10 of the foot 11 of the strip into the space between the edge 12 of the front wall 5 and the adjacent edge portion of the panel 2. The manner in which this is done is more fully illustrated in said prior patent. In this instance, however, the foot is forced directly between the front wall 5 and the panel instead of between that front wall and a shelf or other member. In this case the front wall and the panel itself form the throat through which the foot is forced and which serves to aid in holding the strip in position.

The strip may be of the general form shown in Fig. 6, which is its normal cross-section before being inserted into the mounting. It will be seen that the foot 11 has a surface 13 and that the head 14 of the strip has a surface 15 which normally forms an acute angle with the surface 13. However, when the strip is inserted in place, as shown in Figs. 4 and 5, the foot 11 will be within the recess 8 and the surface 13 will be forced into engagement with the edge 16 of the panel, whereas the surface 15 will be forced into engagement with the face of the panel adjacent the edge and will be compressed between that face and the edge 12 of the wall 5. In other words, the surfaces 13 and 15 will be disposed at right angles to each other or substantially so and the entire strip will be under an internal compression as well as an external compression, tending to return the strip to the form shown in Fig. 6. This internal compression obviously tends to move the foot 11 towards the edge of the panel and thus the panel is tightly held by the foot, and the strip is held in position by the frame and panel.

It will also be noted that the panel is only slightly smaller than the opening 6, preferably just enough smaller so that the panel may be passed through that opening without difficulty.

Thus the rubber strip between the panel and the wall 5 is placed in shear, thus supplying additional strength.

The foot of the strip is not only disposed in the recess 8, but is spaced from the outer wall 11 of the recess, and the toe 10 is likewise spaced from the rear wall 4 so that the foot is free to move outwardly in the recess.

By the above arrangement it will be seen that the panel is supported upon live rubber in such a way that it is firmly held against the backing 7 and it is also resiliently held against outward movement. In case the panel is subjected to a shock or force tending to move it outwardly, not only may the rubber in the foot contract to take up that shock, but the foot itself may bend and move outwardly without contacting with any rigid support. In other words, the panel is floating on live rubber except for the frictional contact between it and the backing.

By referring to Fig. 4, it will be seen that where opposite sides of the frame are provided with strips of rubber constructed and arranged in the manner described above, the foot on one side of the frame will urge the panel against the foot on the other side of the panel so that each edge of the panel is further forced into engagement with the foot of the adjacent strip by means of the compression, internal and external, of the strip on the other side of the frame. The floating action on the mounting is more fully apparent when the strips are thus used on both sides of the mounting of the frame, as is normally the case.

Where the frame is provided with a continual recess 8, as in the present instance, the strips on opposite sides of the frame may be combined into one continuous strip extending around the entire periphery of the opening, as shown in Fig. 1, and having the opposite ends abutting as at 18. Then the entire panel is floating on a live rubber strip which is acting towards the center of the panel from all edges thereof, thus supporting the panel in such a manner as to minimize shock thereto and at the same time to provide a sealing against moisture which is as efficacious as that shown in my aforesaid prior patent.

Another advantage of the mounting arrangement described above is that the construction of the frame is reduced to a very simple form. A simple U-shaped construction, such as illustrated, is sufficient, and the necessity of a shelf outwardly of the edge of the panel is eliminated. The elimination of such ledge or shelf is particularly important at the corners of a frame, particularly where those corners are curved, as is common with the use of the mounting strip

shown herein and in my aforesaid prior patent.

In Fig. 5 I have indicated a projection 19 adjacent the outer surface of the foot 11, but spaced therefrom, preferably a slight distance only. This arrangement is useful where the panel is of such weight or is subject to such vibration or jarring as to cause substantial outward movement of the foot. Such movement will be checked by the projection.

Other advantages no doubt will suggest themselves to those skilled in the art, and likewise various changes in details may suggest themselves and such changes may be made without departing from the scope of the invention, as defined in the appended claims.

I claim:

1. In combination, a panel, a frame extending along an edge of said panel and having a recess disposed outwardly beyond said edge and also having a rear wall overlapping the edge portion of the panel on the back thereof and a front wall spaced from the face of the panel, and a rubber strip having a head compressed between said front wall and the adjacent portion of the face of the panel to force the panel towards said rear wall and also having a foot engaging said edge and disposed in said recess and spaced from the outer wall thereof, the surfaces of said head and foot which engage said face and edge, respectively, normally making an acute angle with each other when out of contact with the panel by being forced away from each other by the panel, whereby said head and foot are pressed inwardly against said face and edge of the panel, respectively.

2. In combination, a panel, a frame extending around the edges of said panel and having a substantially continuous recess disposed outwardly of said edges, said recess having a rear wall overlapping the edge portion of the panel on the back thereof and a front wall spaced from the face of the panel, a rubber strip extending substantially continuously along all edges of the panel, said strip having a head compressed between said front wall and the adjacent portion of the face of the panel to force the panel towards said rear wall and also having a foot engaging said edge and disposed in said recess and spaced from the outer wall thereof, the surfaces of said head and foot which engage said face and edge, respectively, normally making an acute angle with each other when out of contact with the panel by being forced away from each other by the panel, whereby said head and foot are pressed inwardly against said face and edge of the panel, respectively, throughout the entire periphery of the panel.

LYTLE GALE HUNTER.
